UNITED STATES PATENT OFFICE.

OSCAR F. BOOMER AND HENRY R. RANDALL, OF BROOKLYN, ASSIGNEES, BY
MESNE AND DIRECT ASSIGNMENTS, TO THE AUTOMATIC DESULPHURIZ-
ING COMPANY, OF NEW YORK, N. Y.

DESULPHURIZING APPARATUS.

SPECIFICATION forming part of Letters Patent No. 242,870, dated June 14, 1881.

Application filed November 6, 1880. (No model.)

To all whom it may concern:

Be it known that we, OSCAR F. BOOMER and HENRY R. RANDALL, both citizens of the United States, residing at Brooklyn, in the county of Kings and State of New York, have invented new and useful Improvements in Desulphurizing Apparatus, of which the following is a specification.

This invention relates to apparatus for the removal of sulphur from ores by roasting.

Prior to our invention a desulphurizing apparatus has been provided with an endless series of stirrers or scrapers arranged to traverse the roasting-hearth, and hence such feature is not broadly claimed in this application. Furnaces have also been provided with a screw-conveyer for feeding the ore continuously from the hopper to a retort; and in one instance a longitudinally-grooved feed-roller has been arranged below the hopper for feeding the ore upon a series of stationary inclined terraces. The difference between these devices and our invention, in which the rotary intermittent feed-cylinder is arranged within the hopper and adapted to deliver a separate definite quantity of ore to each scraper of an endless series of scrapers, will be apparent from the following specification.

Our invention consists in the combination, in a desulphurizing apparatus, of the horizontal roasting-hearth constituting the bottom of an oblong casing, with a concave at the front end of the hearth below the hopper, a series of scrapers extending across the hearth and carried by endless chains, so as to traverse the hearth and carry the ore over the same, the hopper arranged at the front end of the casing, with a passage-way from the hopper located directly over the concave at the said front end of the hearth, and the intermittent feed-cylinder arranged within the hopper and provided with longitudinal cavities, which receive and deliver a separate and definite charge of crushed ore to each scraper passing over the surface of the concave, as hereinafter more fully set forth.

In the accompanying drawings, Figure 1 is a longitudinal vertical section of an apparatus constructed according to our invention. Fig.

2 is a plan view of the apparatus with a portion of the top of the casing removed.

The letter A indicates a horizontal roasting-hearth arranged upon a furnace, B, of which C is the fire-place. The hearth A is constructed of iron, and forms the bottom of an oblong iron box or casing, A'. Within this box or casing, and at opposite ends thereof, are arranged drums D D', mounted upon transverse shafts d d', journaled in the opposite side walls of the casing, and these drums carry two or more endless chains, E, connected by suitable cross-rods, and provided with transverse scrapers F, extending across the hearth, and arranged at equal distances apart, said scrapers being of such width as to touch the hearth and scrape its surface when the chains are in motion. The shafts d and d' project sufficiently far through the casing at one side of the latter to receive belt-wheels, by which and a suitable belt motion may be transmitted from one to the other, and one of said shafts also carries a belt-wheel for connection with a suitable motor.

Upon the top of the casing, near its front or fire-place end, is arranged a hopper, G, connected with the interior of the casing by a transverse oblong passage-way, h, and within the hopper, at the mouth of said passage-way, is mounted a rotary feed-cylinder, I, preferably of solid cast-iron, and having in its surface longitudinal cavities k. These cavities are of such capacity that when the cylinder is rotated after the hopper is filled with crushed ore, and the chains E are moving in the direction indicated by the arrows, each cavity will carry to the mouth of passage-way h a proper quantity of the ore, to be removed from the end of the hearth upon which it falls by one of the scrapers F, each of said scrapers thus being supplied with a definite quantity of ore, which it can easily move and thoroughly agitate as it traverses the hearth.

At the forward end of the hearth, directly below the hopper and the passage-way h leading therefrom, is a concave, A², constituting a portion of the hearth. The scrapers, in their travel, pass over the surface of this concave, upon which the crushed ore is intermittently

dropped in definite quantities through the passage-way h . This concave does away with such corners in the casing as the ore would be liable to lodge in, and hence all of each charge falling upon the concave will be taken by the scraper which arrives at the concave at the proper moment for taking the said charge. The scrapers are arranged at such distance apart and the speed of travel of chains and rotation of the feed-cylinder is so timed that the scrapers successively arrive in position to remove separately the charges of ore that are intermittently fed or delivered from the feed-cylinder to the passage-way h , through which they drop down upon the concave A^2 . Clogging of the hearth is thus prevented, and a uniform mass of ore is caused to move thereon and be thoroughly agitated and exposed to the heat and air. The feed-cylinder I is rotated by means of a belt-wheel mounted upon the projecting end of one of its journals and connected with another wheel of suitable size upon the shaft d of drum D . When the charges of ore have been moved along the entire length of the roasting-hearth, they are successively dumped into a trough, L , projecting downward transversely from the hearth and open at one end, where it is provided with a spout or chute, l . Longitudinally in the trough L is mounted a conveying-screw, M , consisting of a shaft or cylinder, m , provided with spiral blades m' . One of the journals of this cylinder or shaft projects through the end wall of the trough, and is provided with a belt-wheel, which receives motion through a belt from another wheel of suitable size upon the shaft d' of drum D' . The office of the conveying-screw is to remove the desulphurized ore and deliver it into any suitable receptacle.

From the top of the casing, near its rear end, there leads an air-pipe, N , connected with the induction-pipe of a suction air-draft apparatus, O , which may be operated by belt connection with any rotary shaft of the apparatus or its motor. An entrance-passage, p , for air is arranged near the front end of the top of the casing, and a passage, q , leads from the rear end of the casing to the chimney R of the furnace.

The operation of the apparatus is as follows: 50 The moving parts being suitably connected and put in motion and crushed ore filled into the hopper G , the feed-cylinder I delivers the ore intermittently in definite charges upon the concaved front end of the hearth A , which has 55 been heated to a red heat by the furnace. The scrapers take these charges separately and force them along the surface of the hearth, turning and agitating the ore, so that every particle is exposed thoroughly to the heat and 60 air and the sulphur expelled. The air which is drawn through the casing by the draft apparatus causes combustion of the sulphur, and vapors escape partly to the chimney and partly 65 through the air-pipe N , the desulphurized ore being carried off by the conveying-screw M .

What we claim is—

The combination, in a desulphurizing apparatus, of the horizontal roasting-hearth constituting the bottom of an oblong casing, with 70 the concave A^2 at the front end of the hearth below the hopper, the series of scrapers extending across the hearth and carried by endless chains, so as to traverse the hearth and carry the ore over the same, the hopper arranged at the front end of the casing, with the passage-way from the hopper located directly over the said concave, and the intermittent-feed cylinder arranged within the hopper and provided with longitudinal cavities, which 80 receive and deliver separate and definite charges of crushed ore to each scraper passing over the surface of the concave, substantially as described.

In testimony whereof we have hereunto set 85 our hands and seals in the presence of two subscribing witnesses.
